OIL BURNER

Albert Clarence Johnson, Brooklyn, N. Y.

Application January 11, 1938, Serial No. 184,437

4 Claims. (Cl. 158—77)

This invention relates to oil burners and fuel burning systems of the type particularly adapted for burning heavy fuel oil and comprises an improved burner nozzle structure employing a 5 double rotary cup gasifier of improved design having means associated therewith for continuous preheating of both the fuel oil and air for more thoroughly vaporizing the oil with materially improved flame and combustion of the fuel.

10 Important features of my present improvements consist of a burner construction having a suitably driven rotary gasifier of double or inner and outer cup formation; means to deliver heated fuel oil within the inner cup for vaporization; 15 means for delivering a superheated air volume enveloping the inner cup for further vaporization of the oil; means for delivering a main, combustion supporting, air supply enveloping the outer cup and baffled for swirling intermixture 20 with the combustible gas; an improved assembly providing an air and oil preheating chamber and burner support adapted for attachment to the inner side of a furnace fire door and having an oil heating coil within the chamber for pre- 25 heating of the air and oil from the furnace combustion chamber heat; pump means for normally circulating the oil through the heating coil to a pressure feed tank and thence to the inner cup of the burner; means initially to heat the oil 30 within the pressure tank and for automatically circulating the oil in a cycle by-passing the burner until the determined temperature of the oil is attained and means for automatically opening the feed of the oil to the burner responsive to a de- 35 termined operating pressure and for feeding of the oil from the main tank through the heating coil and to the pressure tank during the burner operation. Further improved features include automatic regulation of the oil feed and air de- 40 livery responsive to boiler steam pressures and other features designed to permit of obtaining the desired temperature regulation of the oil and air for improved combustion.

The described and other features and ad- 45 vantages of the present improvements will be more fully understood by reference to the accompanying drawings wherein like reference characters are applied to the corresponding parts in the several views.

50 In the drawings:

Fig. 1 is a central, vertical, sectional view of a burner structure embodying the features of my invention.

Fig. 2 is a general assembly view showing the 55 burner at right angles to Fig. 1 and in section on

line 2—2 and with diagrammatic illustration of the piping connections with parts shown in section for better understanding thereof.

Fig. 3 is a partial vertical sectional view of the 5 burner on line 3—3 of Fig. 1.

Fig. 4 is a front elevation showing the burner cup arrangement.

Fig. 5 is a vertical sectional view on line 5—5 of Fig. 1.

In the approved embodiment of the features of 10 my invention as here shown, the burner consists of a supporting and bearing member 1 having bearings 2 and 3 for a motor driven shaft or spindle 4. Upon the forward end of the shaft 4 15 there is secured by nut 5 a rotary burner nozzle member having a rear supporting wall or disc portion 6 and inner and outer forwardly open cup members 8 and 9; the former having an annular rearward extension 10 with inturned flange 11. Connecting the spaced cup members 8 and 9, 20 at the rear of the latter, are the radial fan blades 12 and the wall 6 is provided with oil delivery ports 14 as shown. The rotary cup members are enclosed within a stationary nozzle chamber member 15 supported on member 1 and provided 25 with an outer tapered wall, circular in cross-section, spaced from the outer cup 9 and having angularly disposed deflecting blades 16 extending radially inward toward the cup 9. The rear wall 18 of chamber member 15 supports an oil de- 30 livery member 20 of double wall form providing an annular delivery passage 21 opening into the chamber formed by the extension 10.

Encircling the chamber member 15 and secured thereto and also to a vertical wall 25 of the 35 member 1 is an annular heating chamber wall member 26, forming with the wall 25, a heating chamber 27 within which is enclosed an oil heating coil or pipe c which is desirably curved and of corrugated section as shown for increasing the 40 heat exchange surface areas.

The described burner structure, including the 45 vaporizing cup members 8 and 9, chamber member 15 and heating chamber 26 are supported in the furnace fire door opening by attaching of the 50 wall 25 to the usual fire door or to the inner side of the furnace wall and accordingly subjected to the high heat of the furnace combustion chamber to be heated thereby. In accordance with my invention the air preheated in the chamber 27 is 55 passed therefrom inwardly through ports or passages 28 to the fan blades 12 by which it is impelled forwardly in an annular volume immediately contacting and enveloping the vaporized oil from the inner cup 8 whereby a high de- 55

gree of vaporization is effected preparatory to admixture with and combustion by the main air supply entering through the annular passage 30 in encircling relation to the gaseous mixture and 5 swirled by the deflectors 16. The structural arrangement of the ports 28 and annular air passage 30 will be best understood by reference to Figs. 1 and 3 wherein, as shown, the ports 28 extend radially through a jacketing formation of the 10 chamber member 15 providing the annular, horizontal passages 30.

The air supply to the heating chamber 27 and thence to fan 12 is through the passage 32 having atmospheric opening 33 and through the shuttered openings 34—34 as shown in Fig. 2. The 15 main air supply to burner passage 30 enters through ports or openings 35 in a rearward hub formation 36 of the rear plate 37 from which it passes through fan chamber 38 formed by the 20 plate 37 and the bearing member 1 and thence through passages 40 communicating with burner passage 30. The main air supply is impelled by radial fan 42, the hub 43 of which is secured to the shaft 4 as shown. A connecting conduit 44 25 having a valve 45 therein is provided communicating with the heating chamber at 46 and through the hub by port 47 for by-passing heated air from the chamber 27 to preheat the main air supply as desired. In co-operating relation, the 30 passage 32, as shown, is provided with a valve 48 and opens into the lower passage 40 for circulation of air through the heating chamber under the influence of the main air supply fan 42.

The passage of the fuel oil to the burner, as 35 shown in Figs. 1, 3 and 4, is upwardly through the conduit 50 and through connecting conduit 51 to the annular delivery passage 21. From the latter the oil is received within the rapidly 40 rotating rearward extension of the inner cup 8 to which it passes through ports 14; the oil, as will be understood, spreading over and breaking up upon the heated surface of the extension 10 under centrifugal action.

As a further feature of my invention and as 45 best shown in Fig. 2, there is associated with my improved burner arrangement improved means for continuously and uniformly conditioning of the oil and regulating its passage to the burner for maintaining improved conditions of operation. In accordance therewith provision is made 50 for constant circulation of oil from the preheating coil c to a heated oil and pressure tank from which the oil is conducted to the burner. Incorporated therewith is means for initially pre-heating the oil for starting of the burner operation with automatic closed cycle circulation until the 55 desired operating temperature of the oil is attained upon which passage to the burner is permitted and the delivery from the main tank to the heating coil and cycle is opened.

To this end, the improved oil feeding arrangement includes a suitable oil pump 55, which may be a gear pump with gearing connections (not shown) to the burner shaft 4 to operate in a determined ratio thereto. The output of the pump is connected by pipe 58 to a heated oil and pressure tank 58 which is connected to the pump intake by pipes 59, 60, 61 and 62 to establish, when open, an initial or preheating cycle of the 65 oil through the pump and tank. During this starting cycle, means for preheating of the oil in the tank 58 is employed and which is here shown as an electric resistance coil heater 64.

Upon rise of the oil temperature to a determined effective degree, provision is made for

closing the preheating cycle and to then deliver the fuel oil from a main supply tank through the heating element or coil c and through the pump to the tank 58 and when the required pressure therein is built up from the tank 58 to the burner for normal operation with constant delivery of preheated oil to the burner nozzle. The arrangement therefor comprises a pressure actuated valve member v interposed in the pipe 60 having a valve controlled port 64 opening to the burner oil feed pipe 50. The opening of port 64 is controlled by a needle valve 65 carried by a flexible disc 67 within a chamber 68 in communication with pipe 60 through openings 70 whereby pressure within pipe 60 will operate to open the 15 valve 65.

Automatic control for the closing of the initial preheating cycle of oil is effected by means of a thermally responsive relay switch element 72 at the junction of pipes 59—60 which, when sufficiently heated, closes a circuit through leads 74 to the winding 75 of a solenoid valve 76 closing same against seat 77 in opposition to the influence of spring 78 normally moving the armature 79 for opening the valve.

The main oil feed pipe from a suitable supply tank is shown at 80, having check valve 81, and connects at 82 to one end of the preheating element c and at the opposite end, at 83, the heating element is connected by pipe 85 to pipe 62 and the oil pump 55. As a result of the arrangement, insofar as described, upon preheating of the oil from tank 58 by closed cycle circulation through pipes 59, 60, 61, 62, pump 55 and connection 56 under the influence of heating element 64, as explained, the temperature rise will 35 close the relay switch 72 and in consequence the solenoid controlled valve 76. The operation of the oil pump 55 will then raise the pressure in the tank 58 and oil delivery line 59—60 acting on disc 67 to open needle valve 65 for oil delivery to the burner through pipe 50, the oil intake to the burner being constantly from the heated oil tank 58; the renewal supply of oil to the pump and system entering through pipe 80 and passing through heating element c and pipe 45 85 to the pump and to tank 58. A pressure relief valve 86 is provided communicating by pipe 87 with the tank 58 and by return pipe 88 with the oil supply tank for maintaining constant the desired operating oil pressure. The feed of the oil 50 to the burner through pipe 50 is adjustably regulated by means of the set screw 90 arranged to limit the opening of the valve 65.

Further automatic regulation of the burner action is provided to be responsive to the steam pressure generated for which purpose a steam connection 92 is made to the lower portion of valve chamber 68, below the disc 67 whereby excess pressure, as determined, will automatically 60 operate to close the valve 65 and reduce the fuel oil feed to the burner and at the same time provision is made to proportionately reduce the air intake to the burner for supporting the combustion. The latter as shown in Figs. 1 and 5 comprises a rotary shutter valve 94 for reducing the air intake openings 35 and 47, the shutter being supported upon bearing hub 95 having crank extension 96 affixed thereto and connected by link 97 to spring expandible element 98 within a chamber member 99, supported on plate 37, and having steam connection 100 thereto. In operation as will be readily understood, excess of steam pressure will operate through connection 97 to rotate the shutter 94 to cut down the air supply. 70 75

While I have shown and described an approved structural embodiment of the features of my invention it will be understood that varied modifications thereof may be made without departing from the scope of the invention as defined in the appended claims.

Having described my invention, I claim:

- 5 1. An oil burner of the character described comprising a supporting member adapted for attachment to a fire door of a furnace, a rotatable spindle journalled therein, a burner nozzle supported by the supporting member and comprising an outer chamber member and a rotatable vaporizer member positioned in spaced relation to and within the chamber member to provide an outer air passage therebetween, said vaporizer member being connected to the spindle and having spaced inner and outer cup members providing an annular passage therebetween, means for 10 delivering fuel oil within the inner cup member, an air preheater carried by the supporting member in position to surround the outer chamber member and to be exposed to the heat of the furnace combustion chamber, means for impelling preheated air from the preheater through the inner annular passage, means for delivering a main air supply through the outer passage and means for rotating the spindle.
- 15 2. An oil burner of the character described comprising a supporting member adapted for attachment to a fire door of a furnace, a rotatable spindle journalled therein, a burner nozzle carried by the supporting member and comprising an outer chamber member and a rotatable vaporizer member positioned in spaced relation to and within the chamber member to provide an outer air passage therebetween, said vaporizer member being connected to the spindle and having spaced inner and outer cup members providing an inner 20 air passage therebetween, fan blades disposed in said inner passage between the cup members, a preheating chamber member carried by the supporting member and surrounding the outer chamber member in position to be exposed to the furnace heat, means for conducting fuel oil through the preheating chamber and to the inner cup member, means for conducting air direct from the 25
- 30 3. An oil burner of the character described comprising a supporting member adapted for attachment to a fire door of a furnace, a rotatable spindle journalled therein, a burner nozzle comprising an outer chamber member and a rotatable vaporizer member positioned in spaced relation to and within the chamber member to provide an outer air passage therebetween, said vaporizer member being connected to the spindle and having spaced inner and outer cup members providing an inner air 30 passage therebetween, said vaporizer member being connected to the spindle and having spaced inner and outer cup members providing an inner air passage therebetween, means for delivering fuel oil within the inner cup member, an air preheater positioned to surround the outer chamber member and to be exposed to the heat of the combustion chamber, means for delivering air from the preheater through the inner air passage, a fan carried by the spindle, a conduit from said 35 fan for delivering a main air supply to the outer passage, a conduit for by-passing air from the preheater to the main air supply passage, a valve in said by-passing conduit and means for rotating the spindle.
- 35 4. An oil burner of the character described comprising a supporting member, a rotatable spindle, a burner nozzle comprising an outer chamber member and a rotatable vaporizer member positioned in spaced relation to and within the chamber member to provide an outer air passage therebetween, said vaporizer member being connected to the spindle and having spaced inner and outer cup members providing an inner air 40 passage therebetween, means for delivering fuel oil within the inner cup member, an air preheater positioned to surround the outer chamber member and to be exposed to the heat of the combustion chamber, means for delivering air from the preheater through the inner air passage, a fan carried by the spindle, a conduit from said 45 fan for delivering a main air supply to the outer passage, a conduit for by-passing air from the preheater to the main air supply passage, a valve in said by-passing conduit and means for rotating the spindle.

ALBERT CLARENCE JOHNSON.
